UNITED STATES PATENT OFFICE.

JOHN THOMAS BURNS, OF NEW YORK, N. Y.

SELF-PROPELLING HOSE-NOZZLE.

1,176,518.

Specification of Letters Patent. Patented Mar. 21, 1916.

Application filed October 19, 1915. Serial No. 56,723.

To all whom it may concern:

Be it known that I, JOHN T. BURNS, a citizen of the United States, and a resident of the city of New York, Corona, borough 5 of Queens, in the county of Queens and State of New York, have invented a new and Improved Self-Propelling Hose-Nozzle, of which the following is a full, clear, and exact description.

- 10 Among the principal objects which the present invention has in view are:—to provide a nozzle constructed to deliver a boring jet on a line substantially parallel with the axis of the nozzle; to provide rearward openings, forming jets from said nozzle to propel the same by pressure against a volume of water in the rear thereof; and to provide means for varying the effectiveness of the rearwardly directed jets.
- 20 *Drawings.*—Figure 1 is a perspective view of a nozzle constructed and arranged in accordance with the present invention, same being shown in conjunction with an end fragment of hose pipe; and Fig. 2 is a longitudinal section of said nozzle.

Description.—The nozzle herein described and shown in the accompanying drawings, is specifically designed for cleaning sewer pipe of relatively small dimensions. In performing this work, a flexible hose pipe is employed and the nozzle is dropped into the sewer and forced or induced to follow the sinuosities of the same. This practice has been fraught heretofore with difficulties incident principally to the back pressure of the water delivered from the hose pipe, which has resisted the pressure applied to the hose to force the same through the sewer pipe. When employing a nozzle constructed and arranged in accordance with the present invention, it is found that the obstructive pressure referred to is totally avoided and that a propelling or drawing impulse is imparted to the nozzle and hose connected therewith, 45 while performing to a marked degree, the desired cleansing or scouring of the walls of the sewer pipe through which it is passing.

As seen in the drawings, a nozzle when constructed and arranged in accordance with 50 the present invention, has a neck 7, the screw-threaded section 8 whereof is operatively attached to a hose pipe 9 by means of a threaded end or nut 10 conventionally mounted thereon. The neck 7 is integrally formed with a balloon-shaped body 11, the

enlarged chamber 12 whereof is tapered forwardly to form a contracted passage 13 from which a jet is forcefully emitted, the object being to break down by the impact of water delivered from the hose pipe 9, any obstacle 60 in the path of the nozzle and hose.

The chamber 12 is centrally bellied or spread to form a rearwardly turned wall. This wall is pierced at several points to receive bushings 14, which are provided with 65 screw threads and secured in the tapped holes formed in the body 11. The bushings 14 are centrally bored to form delivery passages 15. These passages as seen best in Fig. 2 of the drawings are so disposed as to give 70 a rearwardly inclined direction to water leaving the chamber 12.

While I have herein described the use of the bushings 14, it will be understood that I may dispense with such and provide the 75 body 11 with delivery apertures, cast or otherwise formed therein. I prefer, however, to use the bushings 14, as by so doing, I may employ a number of bushings having different sized passages to form variously 80 sized jets and in so doing change the action of the nozzle to increase the speed of propulsion thereof at the expense of the scouring of the side walls of the sewer pipe, or to increase the effective scouring of the sewer 85 pipe at the expense of the rapidity of travel of the nozzle.

Claim:

A hose nozzle comprising a transversely extended chambered body having forwardly 90 and rearwardly faced walls; a propeller for moving said nozzle in a forward direction, said propeller embodying openings in the rearwardly faced wall of said body for delivering the contents of said body in a rearward direction therefrom; and means for clearing the path of said body, said means embodying a relatively contracted delivery opening in the front wall of said body for increasing the speed of delivery of the contents of said body and diminishing the resisting area of the material leaving said body.

In testimony whereof I have signed my name to this specification in the presence of 105 two subscribing witnesses.

JOHN THOMAS BURNS.
